THREAD CONTROL FOR WEFT RE-PLENISHING LOOMS

Richard G. Turner, Worcester, Mass., assignor to
Crompton & Knowles Loom Works, Worcester,
Mass., a corporation of Massachusetts

Application May 21, 1945, Serial No. 594,925

23 Claims. (Cl. 139—247)

1

This invention relates to improvements in weft replenishing looms and it is the general object of the invention to relate the bobbin magazine and thread control devices in such manner as to improve the operation of the loom with respect to the weft ends of the reserve bobbins and also the threads of both the incoming and the outgoing bobbins which are involved in a replenishing operation.

In the past it has been customary to provide a magazine in which the reserve bobbins have their weft ends led outwardly away from the center of the loom to a thread holder and provide additional means between the magazine and the fabric for removing weft ends which are left incident to a replenishing operation. With such an arrangement the thread of a freshly transferred bobbin which extends from the thread holder to the cloth lies under the magazine where it can become entangled with bobbins which are moved downwardly during later transferring operations. Furthermore, when the thread holder is at the outer end of the loom, some difficulty has been experienced in controlling the path of the thread or weft ends as the latter move downwardly in the magazine toward transfer position. It is an important object of my present invention to locate the thread holder between the magazine and the center of the loom and lead the weft ends from the bobbin tips inwardly toward the thread holder. In this way the thread of the incoming bobbin subsequent to transfer does not extend under the magazine and therefore cannot interfere with subsequent transfers.

In weft replenishing looms as made heretofore it has been customary to provide two different mechanisms, one to control the thread extending from the incoming bobbin and the other to control the thread leading to the outgoing bobbin. These two mechanisms are ordinarily on opposite sides of the magazine, the first being a thread holder on the outer end of the magazine and the second being a thread remover on the inner end of the magazine. It is another important object of my present invention to combine these two mechanisms and locate them adjacent to the inner end of the magazine between the latter and the center of the loom and in such a position that all the weft ends of the reserve bobbins and the thread of the outgoing bobbin can be led to a common point above the lay. As shown herein I utilize a pneumatic thread controlling device having a single inlet mouth which receives all of the previously mentioned threads.

The usual magazine has a supporting foot secured to the loom frame and connected to the inner end of the magazine. Such a foot would

2

interfere with threads extending from the reserve bobbins in the magazine to a thread holder located between the magazine and the center of the loom, and in order to avoid this interference it is a further object of my present invention to provide means for supporting the magazine at the outer end thereof, thereby leaving a free uninterrupted space around the inner end of the magazine for the weft ends of the bobbins in the magazine. In this connection I also provide means for mounting the bobbin transerrer arm so that it is supported near the outer end of the magazine where it will not interfere with the aforesaid weft ends.

In order to effect correct threading of the shuttle subsequent to a transfer operation it is desirable to locate the thread holder in a position somewhat to the rear of the lay when the latter is on front center. When so located, however, the usual mechanisms employed to place the thread of the outgoing bobbin for removal would be ineffective, since such mechanisms ordinarily are located in front of the lay. It is a further object of my invention to provide thread controlling mechanism having an intake mouth or the like correctly located for the thread holding function thereof, and in addition provide a thread placing mechanism which will move the thread of the outgoing bobbin upwardly and then rearwardly toward the intake mouth. This latter feature of my invention lifts the outgoing thread over the back of the shuttle box to the aforesaid single intake mouth.

When pneumatic thread holders are used in the conventional position beyond the magazine it is frequently difficult to detach the thread of a transferred bobbin from the reserve bobbin weft ends entering the intake mouth so that it can be drawn into the latter when cut at the selvage. It is another feature of my invention to locate the intake mouth in such position that the weft ends of the reserve bobbins and the thread of the transferred bobbin immediately after transfer approach the mouth from one direction, and cause the shuttle by its motion incident to picking to separate its thread from the weft ends and approach the mouth from the opposite direction. When the thread is later cut at the selvage it will not be caught under the weft ends in the intake mouth but can enter the latter freely for effective removal.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a side elevation of part of a loom having my invention applied thereto, parts being in section,

Fig. 2 is an enlarged front elevation looking in the direction of arrow 2, Fig. 1,

Fig. 3 is a plan view looking in the direction of arrow 3, Fig. 2,

Fig. 4 is a side elevation on a reduced scale looking in the direction of arrow 4, Fig. 2, the shuttle and lay being in section,

Fig. 5 is a detailed vertical section on line 5—5 of Fig. 3 on an enlarged scale,

Fig. 6 is a reduced plan partly in section of the breast beam of the loom and the extension which supports the magazine looking in the direction of arrow 6, Fig. 2,

Fig. 7 is an enlarged vertical section on line 7—7 of Fig. 3 showing the mechanism for moving the thread of the outgoing bobbin toward the intake mouth of the thread control mechanism,

Figs. 8 and 9 are diagrammatic views showing successive positions of the thread placer shown in Fig. 7 as the thread of the outgoing bobbin is lifted to the thread intake mouth, and

Fig. 10 is a diagrammatic view showing two threads extending from the selvage to the thread holder, one thread corresponding to an incoming bobbin and the other to an outgoing bobbin.

Referring to Fig. 1, I have shown a loom frame 10, lay 11, top shaft 12, lay connector 13, air pump 14 and a lever 15 operating the air pump by means of a connecting rod 16 attached to the lay. A pipe or air conduit 17 extends forwardly from the pump and the latter operates during the rearward strokes of the lay to create subatmospheric pressures within the conduit. The lay has a shuttle box 18 to receive a shuttle S which carries a weft bobbin B. The lay reciprocates between front and back center positions in usual manner due to rotation of shaft 12, and the shuttle is ordinarily picked when the lay is about at the mid point in its backward stroke. The loom frame 10 includes in its construction a breast beam 19 which may be formed of angle iron or the like as suggested in the left hand part of Fig. 6.

A rocking mechanism designated generally at 20 has a depending rod 21 controlled by mechanism not shown and is provided also with a forwardly extending rod 22 which effects rocking of the magazine indicated generally at M.

The matter thus far described may be usual construction and made for instance according to my prior Patent No. 2,199,353.

In carrying my present invention into effect I provide means for supporting the magazine M adjacent to the outer end thereof so that there may be a free space around the inner end of the magazine for threads which lead to thread control mechanism located between the magazine and the center of the loom. The previously mentioned breast beam has a horizontal web 25 and a depending web 26 which is to the rear of the web 25. In order to provide a support for the magazine M I weld or otherwise secure a plate 27 to the breast beam 19 and secure to said plate a support or angle iron 28 which in effect is a continuation of the breast beam. Support 28 has a depending flange 29 and a horizontal top plate 30. The support 28 is made sufficiently strong to support the magazine and parts associated therewith and the vertical flange 29 is disposed at the front of the support for reasons which will appear presently.

Secured to the support 28 is a stand 35, see

Fig. 2, the upper end of which is provided with a hub 36 through which passes a tubular pivotal support 37 for the magazine. The tube 37 is clamped in fixed position on the hub 36 by bolts 38.

The magazine comprises inner and outer bobbin guiding plates 40 and 41, respectively, connected together by tie rods 42 and rocking as a unit about the tubular support 37. The previously mentioned forwardly extending rod 22 is connected as at 43 to the inner plate of the magazine so that the latter may be rocked to assume either of two operating positions. The inner plate 40 is provided with guideways 44 for the heads of reserve bobbins W, while the outer plate 41 is provided with similar but narrower guideways 45 for the tips of the bobbins W. The bobbins are arranged in two groups as indicated in Fig. 4 and feed downwardly by gravity toward transfer position, each stack having its own transfer position and the magazine rocking so that the lowest bobbin of either stack may be brought to transfer position.

The inner plate 40 of the magazine may be formed substantially as shown in Fig. 4 and has front and back smooth thread engaging surfaces 50 and 51, respectively, which are connected at their lower ends by a thread engaging surface 52. These three surfaces 50, 51 and 52 are continuous so that they offer no interruption to the downward movement of the weft ends or threads T extending from the bobbins W.

It will be apparent from Fig. 3 that the threads T, instead of being extended to the right as is usual, extend toward the left or toward the center of the loom from the tip ends of the bobbins and extend around the surfaces 50 and 51 to a thread holder designated generally at H. This holder is of the pneumatic type and has an intake mouth 53 which opens toward the center of the loom.

The thread holder is formed preferably of a metal tube 55, the upper end of which is formed with a head 56 secured to the left end of a hollow tubular support 37 by a set screw 57, as indicated in Fig. 2. The thread intake mouth 53 is therefore in pneumatic communication with the interior of the tubular support 37. The latter is extended beyond the hub 36 and has supported thereon a thread collector 58, the upper end of which is connected to the previously described conduit or pipe 17. The thread collector is a closed chamber and may be made according to my aforesaid patent except for the manner of its mounting. During each backward stroke of the lay subatmospheric pressures are created within the thread collector 58 and the tubular support 37, therefore creating an inrush of air into the intake mouth 53. The weft threads T leading from the reserve bobbins in the magazine extend into the intake mouth 53 and are subjected to pneumatic attraction which holds them taut during loom operation.

In order to effect transfer of a bobbin whenever a replenishing operation is called I provide a transfer arm 60 which is located near the outer end of the magazine. This arm 60 has a horizontal extension 61 from the left end of which as viewed in Fig. 2 depends a hammer 62 for engagement with the butt ends of the bobbins. A bobbin tip guide 63 may also be extended downwardly from the extension 61. The transfer arm has a hub 64 which is secured to a shaft 65, and a relatively heavy coil spring 66 surrounds the hub 64 and has one end thereof

operatively engaging the transerrer arm and has the other end thereof held in fixed position with respect to the stand 35. The latter is provided with a hub 61 which provides ample support for shaft 65. The latter and the transerrer arm are secured together and therefore move angularly in unison, and the spring 66 acts in the usual manner to hold the transerrer arm normally raised as indicated in Fig. 1.

As viewed in Figs. 2 and 3 the shaft 65 extends to the left from the transerrer arm and passes through and is rotatable in a bearing 70 mounted on the support 28. A latch arm 71 is secured to shaft 65 and a transfer latch 72 is pivoted thereto as at 73. The latch is normally down as shown in Fig. 4, but can be raised by a lifter 74 when the latter moves upwardly to set the magazine for transfer preparatory to a replenishing operation. Such a lifter is shown in Patent No. 2,234,622. Upward movement of the lifter 74 will raise the latch so that it will be in the path of a bunter 75 on the lay 11. The latch carrying arm 71 extends downwardly through a slot 76 formed in the horizontal flange 30 of the support 28. When the transerrer latch is lifted it will be engaged by the bunter on the advancing lay and moved forwardly or to the left as viewed in Fig. 5 to rock shaft 65 in a clockwise direction, thereby depressing the transerrer arm to effect transfer of the bobbin under it.

At the time of transfer a thread T' will extend from the shuttle in the box 18 toward the center of the loom, and in order to prevent this thread from being drawn into the warp shed I provide means to lift it to a point adjacent the intake mouth 53. This mechanism is shown in Fig. 7, and comprises an arm 80 secured to the inner end of the shaft 65 and extending rearwardly therefrom. This arm is adapted for engagement with a lever 81 pivoted as at 82 to a small stand 83 fastened preferably to the breast beam 19. Lever 81 has an upper arm 84 for engagement with the underside of the arm 80, and has also a lower arm 85 which is pivoted as at 86 to a floating thread placer 87. The forward end of the latter is provided with a roll 88 which slides in a cam groove 89 formed in a cam plate 90 secured to the breast beam. The rear end of the placer 87 may be notched as at 91 to receive thread T' and lies normally under the shuttle race 92, the lay being provided with a transverse groove 93 for this purpose. The groove 93 leads rearwardly to a vertical box back 94 secured to the lay and forming part of the previously described shuttle box 18. A spring 95 normally acts to hold the placer 87 in forward position, or in the full line position as shown in Fig. 7.

At the time of a transferring operation arm 80 is depressed as shaft 65 rocks and engages the upper arm 84 of lever 81, rocking the latter in a counter-clockwise direction as viewed in Fig. 7 and moving the thread placer 87 rearwardly or to the right. This occurs during the latter part of the forward movement of the lay on a replenishing beat of the loom, and the groove 89 is so formed as to cause the rear end of the thread placer 87 to traverse the path designated by dot and dash line a in Fig. 7. This path of the rear end of the thread placer leads to the intake mouth 53 and the thread T' extending from the shuttle in box 18 is thus lifted to a point where it can be attracted by the draft of air moving into the intake mouth. As soon as the lay starts to move rearwardly a partial vacuum will be set up within the pneumatic thread removing system and

the thread T' will be drawn into the mouth 53, having previously been cut at a point adjacent to the shuttle eye by well-known means not shown. The right end of groove 89 is so formed that the notched end 91 of the thread placer 87 will move across the intake mouth 53 and hold the thread T' in position where it can be attracted by the pneumatic thread holder during the first part of the upward movement of the transerrer arm as the lay begins to move rearwardly subsequent to completion of a transferring operation.

Figs. 8 and 9 indicate diagrammatically the successive positions which the thread placer 87 and notch 91 move during a thread placing operation. During the first part of the operation the placer 87 passes through the positions I, II, and III, Fig. 8, lifting the notch 91 along the front of box back 94. As the operation continues through positions IV, V and VI, Fig. 9, the notch rises over and passes behind wall 94, ultimately reaching the position shown in dotted lines, Fig. 7.

Under normal operation the lay reciprocates backwardly and forwardly and the transerrer arm and latch 72 remain in idle position, thread placing operation arm 80 is up, and the thread placer 87 is down as in full lines, Fig. 7. Drafts of air are drawn intermittently into the thread holder H to create tension in all of the weft ends or threads T extending from the reserve bobbins in the magazine. When a transferring operation is indicated by mechanism not shown herein but well understood, the lifter 74 will raise the latch to operating position and as the lay advances the transerrer arm will descend as already described, and arm 80 will also be lowered. As a transferring operation proceeds the thread placer 87 is raised as already described and moves the thread T' upwardly and then rearwardly with respect to the box back 94 toward the intake mouth 53. During transfer the bobbin W under the transerrer arm moves into shuttle S and its thread descends. After the transfer operation is completed the lay moves rearwardly and the replenished shuttle is picked. The thread attached to the freshly inserted bobbin in the shuttle extends along the under surface 52 of the inside plate 40 and then upwardly to the intake mouth. As the shuttle is picked it moves to the left as viewed in Fig. 2 or in a general direction toward the intake mouth and the slack thus created in the thread extending from the fresh bobbin is drawn into the thread holder. As the shuttle passes the thread holder thread begins to unwind from the bobbin and in doing so becomes at least partially threaded in the trailing end of the shuttle. The shuttle will be made in usual manner and will be provided with a self-threading eye.

That part of the thread T' which is adjacent to the selvage of the cloth and was attached to the outgoing bobbin will extend upwardly from the selvage to the intake mouth and on the first beat-up after transfer the thread T' and the thread of the freshly transferred bobbin will both extend from the selvage to the thread holder. The usual form of temple cutter, see Fig. 10, will serve to cut these threads on some subsequent forward beat of the lay, whereupon they will both be drawn into the thread holder and move through the tubular support 37 to the thread collector or accumulator 58, where they will be held as described in my Patent No. 2,199,353.

Fig. 10 indicates diagrammatically an advantage growing out of a pneumatic thread control system having a common mouth for the threads

of both the outgoing and the incoming bobbins. Certain types of coarse weft are hairy and tend to cling to each other due to projecting fibers. When weaving with such yarns the threads of both the outgoing and incoming bobbins may be matted together during cutting at the selvage and become in effect a single strand. When the thread remover and the thread holder have separate mouths as in constructions heretofore proposed the ends of the strand are pulled in opposite directions by the remover and holder, and neither of these devices is able to remove the strand from the loom. This condition cannot occur with my present invention.

Referring to Fig. 10, the fabric F has extending therefrom one of the threads T which was connected to the incoming bobbin and also thread T' which was connected to the outgoing bobbin. The cutter mechanism C close to the selvage operates to cut these threads several picks after transfer, and during cutting both of these threads may be matted together, as indicated at K. It will be understood from Fig. 10, however, even if these threads do cling together they will be drawn into the intake mouth 53 and effectively removed from the loom because of the fact that a single intake mouth is provided for both threads.

Another feature of the invention will be apparent from a consideration of Figs. 2 and 4. The weft ends of the front stack of bobbins enter and extend along the right hand side of the intake mouth 53 as shown in Fig. 4, while the weft ends of the rear stack of bobbins enter and extend along the back part of the mouth 53. When a bobbin is transferred from one or the other of the stacks, the shuttle S will be under the magazine and to the right of the intake mouth 53 as viewed in Fig. 2, but during picking the shuttle will pass by the intake mouth to the left and thereby draw its thread after it. Prior to picking the thread of the transferred bobbin may be caught under one or another of the weft ends of the group corresponding to it, and this thread along with the weft ends will approach the intake mouth in a direction toward the fabric, or from the outer end of the lay, but during picking and due to motion of the shuttle the thread will be detached from its group of weft ends and have its direction of approach to the mouth reversed and extend toward the intake mouth in a direction away from the fabric. When this thread is later cut at the selvage by the cutter C, Fig. 10, it can be drawn readily into the intake mouth 53 because it is free from the weft ends in the mouth and will not be entangled by them.

From the foregoing it will be seen that I have provided an improved form of thread control for weft replenishing looms wherein the thread holder is located between the magazine and the loom so that the thread of a freshly transferred bobbin will not extend under the magazine. This is of particular importance in multicolor weft replenishing looms in which successive transfers can occur, the later transfer occurring before the thread of an earlier transfer has been cut at the selvage and removed by the thread holder. It will also be seen that the thread extending from the thread holder lies along a path to the left of the shuttle boxes viewed in Figs. 2 and 3 and therefore will not become entangled with any parts of the shuttle box as the lay reciprocates. Furthermore, the transerrer arm is located adjacent to the outer end of the magazine and therefore does not interfere with the weft ends

extending from the reserve bobbins to the thread holder. The thread placer 87 operates not only to lift the thread of the outgoing bobbin but also moves it rearwardly with respect to the box back 94 toward the intake mouth 53. This latter provision is desirable because it is of importance to have the thread holder located far enough behind the lay when the latter is on front center position to effect at least partial self-threading of the shuttle on the pick immediately following a replenishing operation. It will also be noted that when the shuttle is picked it reverses the direction of approach of the weft end of the transferred bobbin with respect to the intake mouth 53, and in doing so detaches this thread from the group corresponding to it so that upon subsequent cutting at the selvage the thread can be drawn into the mouth without interference by the other threads which approach the mouth from a different direction.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom wherein a replenishing operation leaves two threads to be removed, one from the outgoing bobbin and the other from the incoming bobbin, and wherein provision is made for cutting both of these threads at the selvage, a pneumatic thread control mechanism having an intake mouth into which one end of the thread of the incoming bobbin normally extends, means incident to a weft replenishing operation to move the thread of the outgoing bobbin to a point adjacent to said intake mouth, and means to induce a draft of air into said intake mouth to draw both of said threads into said mouth when said threads are cut at the selvage.

2. In a weft replenishing loom wherein a thread corresponding to the incoming bobbin and another thread corresponding to the outgoing bobbin remain for removal incident to a replenishing operation, a pneumatic thread control device in which subatmospheric pressures exist and having an intake mouth, the thread of the incoming bobbin normally extending into said mouth, thread placing means operating incident to a replenishing operation to move the thread corresponding to the outgoing bobbin to a point adjacent to said intake mouth, and means to cut said threads at the selvage subsequent to operation of said thread placing means.

3. In a weft replenishing loom in which two threads extend from the selvage subsequent to a replenishing operation, one of said threads corresponding to the incoming bobbin and the other thread corresponding to the outgoing bobbin, the loom having provision for cutting said threads at a point adjacent to the selvage, a pneumatic thread controller in which subatmospheric pressures exist and having an intake mouth into which the thread of the incoming bobbin normally extends, and means operative incident to a replenishing operation of the loom to move the thread of the outgoing bobbin to a point adjacent to said intake mouth.

4. In a weft replenishing loom wherein two threads extend from the selvage subsequent to a replenishing operation, one of said threads corresponding to the incoming bobbin and the other thread corresponding to the outgoing bobbin, the loom having provision for cutting both of said

threads adjacent to the selvage and said threads being of such nature as causes them to tend to cling to each other as a result of the cutting operation, a single pneumatic thread removing mechanism in which subatmospheric pressures exist, said mechanism having an intake mouth into which the thread corresponding to the incoming bobbin normally extends, and means to move the thread corresponding to the outgoing bobbin to a point adjacent to said intake mouth prior to cutting of said threads at the selvage.

5. In a weft replenishing loom having a pneumatic thread removing system in which subatmospheric pressures exist, said system including an intake mouth into which extends one end of a thread corresponding to the incoming bobbin involved in a replenishing operation, the loom having a second thread corresponding to the outgoing bobbin involved in said replenishing operation and having also means for cutting both of said threads adjacent to the selvage, and mechanism operating incident to said replenishing operation to move the thread corresponding to the outgoing bobbin to a point adjacent to said intake mouth prior to cutting of said threads at the selvage.

6. In a weft replenishing loom having a lay provided with a shuttle box from which a thread extends to the adjacent selvage incident to a replenishing operation, a pneumatic thread remover having an intake mouth into which air is drawn, said mouth being located above and behind the shuttle box during a replenishing operation of the loom, and means operative during a replenishing operation of the loom to move said thread upwardly to a point above said shuttle box and then rearwardly to a point adjacent to said intake mouth.

7. In a weft replenishing loom having a lay provided with a shuttle box from which a thread extends to the adjacent selvage incident to a replenishing operation, a pneumatic thread remover having an intake mouth into which air is drawn, said mouth being located above and behind the shuttle box during a replenishing operation of the loom, a thread placer normally located under said thread, and means operative at the time of a replenishing operation of the loom to cause said placer to move the thread over and rearwardly with respect to said shuttle box to a point adjacent to said intake mouth.

8. In a weft replenishing loom having a lay provided with a shuttle box from which a thread extends to the adjacent selvage incident to a replenishing operation, a pneumatic thread remover having an intake mouth located above and behind the shuttle box during a replenishing operation of the loom, a thread placer normally under said thread and located between the shuttle box and the selvage, and means operating incident to a replenishing operation to cause said thread placer to move a portion of that part of the thread extending between the shuttle box and the selvage upwardly and rearwardly with respect to the shuttle box to a point adjacent to said intake mouth.

9. In a weft replenishing loom having a reserve bobbin from which a weft end extends and wherein said weft end and an additional thread extend from and are cut at the selvage subsequent to a replenishing operation involving said bobbin, and a combined thread holder and thread remover in which subatmospheric pressures exist, said combined thread holder and remover having an intake mouth into which said weft end ex-

tends and to which said additional thread is presented incident to a replenishing operation to enable said combined thread holder and remover to control both the weft end and said additional thread subsequent to cutting thereof at the selvage.

10. In a weft replenishing loom having a reserve bobbin from which a weft end extends, said weft end and an additional thread extending from and being cut at the selvage subsequent to a replenishing operation involving said bobbin, a combined thread holder and thread remover in which subatmospheric pressures exist and having an intake mouth into which said weft end extends, and means moving said additional thread to a point adjacent to said intake mouth incident to said replenishing operation and prior to cutting of said weft end and thread at the selvage, whereby both said weft end and said thread are drawn into said combined thread holder and remover subsequent to cutting thereof at the selvage.

11. In a weft replenishing loom having a reserve bobbin from which a weft end extends, said weft end and an additional thread extending from and being cut at the selvage subsequent to a replenishing operation involving said bobbin, a pneumatic thread collector in which subatmospheric pressures exist, a pneumatic combined thread holder and thread remover pneumatically connected to said thread controller and having an intake mouth into which said weft end normally extends and to which said additional thread is presented incident to said replenishing operation, whereby both said weft end and said additional thread are drawn into said intake mouth and to said thread collector.

12. In a weft replenishing loom provided with a reserve bobbin magazine having an inside bobbin butt guiding plate and an outside bobbin tip guiding plate and in which reserve bobbins extend between said plates and move downwardly to a transfer position, a pneumatic thread holder having an intake mouth located between said inside plate and the cloth in the loom, and means on said inside plate defining an outside smooth thread guiding surface, the weft ends of the bobbins leading from points adjacent to said outside plate around said smooth surface of the inside plate to said intake mouth and moving down said surface as the bobbins descend.

13. In a weft replenishing mechanism having two stacks of reserve bobbins and having an inside plate to guide the butts of said bobbins and having an outside plate to guide the tips of said bobbins, a pneumatic thread holder having an intake mouth on that side of the inside plate opposite to the outside plate, and means on opposite sides of said inside plate defining smooth uninterrupted yarn guiding surfaces, one of said surfaces for each stack of bobbins, the weft ends of each stack of bobbins leading from their tips around the corresponding smooth surface to said intake mouth.

14. In a weft replenishing loom provided with a magazine having a stack of reserve bobbins the butt ends of which are toward the center of the loom and the tip ends of which point away from the center of the loom, an inside plate to guide the butt ends of said bobbins as the latter move downwardly to transfer position, an outside plate to guide the tips of the bobbins, a pneumatic thread holder having an intake mouth between said inside plate and the center of the loom, and means on said inside plate defining a

11

smooth yarn engaging surface, the weft ends extending from the tip ends of the bobbins inwardly toward said inside plate and around said smooth surface and then to said intake mouth.

15. In a weft replenishing loom having a frame, a magazine for reserve bobbins comprising an inside plate adjacent to the center of the loom and an outside plate remote from the center of the loom, means to support the outside plate with respect to said frame, other means to support said inside plate from said outside plate, and a pneumatic thread holder supported by the magazine and having an intake mouth located between said inside plate and the center of the loom, said inside plate having a free space entirely surrounding the same so that weft ends leading from bobbins in the magazine to said intake mouth can move downwardly uninterruptedly from the top to the bottom of the magazine as their respective bobbins descend in the magazine.

16. In a weft replenishing loom having a frame and operating with two stacks of reserve bobbins, a magazine having an inside plate to guide said bobbins and located adjacent to the center of the loom, an outside plate forming part of the magazine and spaced from said inside plate in a direction away from the center of the loom, means to support said outside plate with respect to said frame, other means to support said inside plate from said outside plate, and a pneumatic thread holder having an intake mouth located between said inside plate and the center of the loom and supported by said inside plate, whereby a free space exists entirely around said inside plate for the passage of weft ends from either of said stacks to said intake mouth.

17. In a weft replenishing loom having a group of weft ends, a pneumatic thread holder within which subatmospheric pressures exist having an intake mouth opening toward the fabric in the loom, and a shuttle having a thread extending therefrom, the weft ends and thread approaching the intake mouth in a direction toward the fabric in the loom and entering the mouth, the shuttle after being picked in a direction toward the fabric causing the thread to approach the mouth in a direction from the fabric toward the mouth.

18. In a weft replenishing loom having a reserve bobbin magazine from which weft ends extend, a shuttle under the magazine having a thread extending therefrom, and a pneumatic thread holder in which subatmospheric pressures exist having an intake mouth which the weft ends and thread approach in a general direction toward the fabric in the loom, the shuttle when picked in a direction away from the magazine and toward the fabric reversing the direction of approach of said thread to the intake mouth and causing said thread to enter said mouth in a direction from the fabric toward the mouth.

19. In a weft replenishing loom having a magazine from which weft ends extend, a shuttle under the magazine from which a thread extends, and a pneumatic thread holder in which subatmospheric pressures exist having an intake mouth intermediate the magazine and the fabric in the loom, the weft ends and thread prior to picking of the shuttle approaching said intake mouth in directions from the magazine and shuttle toward the fabric, the shuttle subsequent to picking causing reversal in the direction of approach of the thread toward said mouth.

20. In a weft replenishing loom having a reserve bobbin magazine from which weft ends extend, a shuttle under the magazine having a

12

thread extending therefrom, and a pneumatic thread holder in which subatmospheric pressures exist having an intake mouth located intermediate the shuttle and fabric and toward which

5 the weft ends and thread approach in a direction toward the fabric, the shuttle incident to picking thereof passing said intake mouth and causing a reversal in the direction of approach of said thread toward the mouth.

10 21. In a weft replenishing loom, a pneumatic thread holder within which subatmospheric pressures exist having an intake mouth opening toward the fabric in the loom, the loom having a group of weft ends approaching the mouth in 15 a direction toward the fabric and entering the latter, and a shuttle having a thread extending therefrom approaching said mouth in the general direction of approach of said weft ends and entering said mouth, the shuttle when picked 20 toward the fabric moving said thread therewith and causing the latter to approach said mouth in a direction from the fabric toward the mouth.

22. In a weft replenishing loom having a magazine with reserve bobbins from which weft ends extend, a shuttle under the magazine having therein a bobbin freshly transferred from the magazine and from which a thread extends, and a pneumatic thread holder within which subatmospheric pressures exist having an intake mouth receiving said weft ends and thread between the magazine and fabric and toward which said weft ends and thread approach in a direction from the magazine toward the cloth, the shuttle when picked from under the magazine 30 toward the fabric drawing said thread therewith and causing the same to enter said mouth in a direction from the fabric toward the magazine.

23. In a weft replenishing loom having a selvage cutter and a magazine with reserve bobbins from which weft ends extend, a shuttle under the magazine having therein a bobbin freshly transferred from the magazine and from which a thread extends, and a pneumatic thread holder within which subatmospheric pressures exist 40 having an intake mouth receiving said weft ends and thread between the magazine and fabric, the shuttle when picked from under the magazine toward the fabric drawing said thread therewith and causing the same to enter said mouth in a direction from the fabric toward the magazine, and said thread when cut by the selvage cutter entering the intake mouth in a direction opposite to that in which the weft ends approach the mouth.
